COIN CONTROLLED PERFUME DISPENSER

James A. McDevitt, Philadelphia, Pa.

Application May 6, 1954, Serial No. 30,361

Term of patent 3½ years

(Cl. D52—3)

Fig. 1 is a front perspective view of a coin controlled perfume dispenser showing my new design;

Fig. 2 is a top plan view on a somewhat reduced scale; and

Fig. 3 is a side elevational view, also on a reduced scale.

I claim:

The ornamental design for a coin controlled perfume dispenser, as shown.
